WINDOW LATCHING DEVICE

Michael Rifkin, Lyndhurst, N. J.

Application December 13, 1956, Serial No. 628,073

11 Claims. (Cl. 292—149)

This invention relates generally to improvements in window construction, and, more particularly, to improvements in a latching device therefor.

In my application Serial No. 602,031, filed on August 3, 1956, for Window Construction, there is disclosed a latch arrangement having novel means for locking sashes in a closed, or near closed, condition in a burglarproof manner and the primary aim and object of the present invention is the provision of a latch arrangement of a generally similar character having improved means for locking sashes in a burglarproof manner.

Another important object of the present invention is the provision of an improved latch device of the aforesigned character which is of simple design and construction, easy to install and service, and which is eminently suitable in the accomplishment of its intended purposes.

Other objects, features and advantages of the invention will become apparent as the description thereof proceeds when considered in connection with the accompanying illustrative drawing in which:

Fig. 1 is a fragmentary horizontal sectional view showing a sash stile and associated latch device of the present invention with the latch device in an unlocked condition;

Fig. 2 is a view similar to Fig. 1 with the latch device shown in a locked condition;

Fig. 3 is a fragmentary side view of the latching member of the latch device with the lock screw installed;

Fig. 4 is a top view thereof shown partially in section;

Fig. 5 is a view similar to Fig. 3 showing a modified form of latching member and lock screw;

Fig. 6 is a view similar to Fig. 4 corresponding to the latching member of Fig. 5;

Fig. 7 is a view similar to Fig. 3 showing another form of latching member and lock screw; and

Fig. 8 is a view similar to Fig. 2 showing another form of latch device.

Referring to the drawing in detail, there is shown a window construction 10 of the general type disclosed in my above referred to patent application and in my Patent No. 2,694,237 for Window Construction issued on November 16, 1954, said window construction including sashes 12, each of which is mounted for vertical reciprocation between a companion pair of runners, one of which is fixed with the opposite one being laterally movable towards its associated jamb member against the action of spring means disposed between said jamb member and the movable runner.

The latch device 14 of the present invention shown in Figs. 1-4 is generally similar to the latch device shown in Figs. 16-20a of my aforesigned copending application and said latch device is secured in the recess or mortise 16 of a companion sash stile 18. The latch device 14 incorporates an improved anti-burglary feature so that the sashes may be locked in a closed, or near closed, position in a burglarproof manner as will be described in detail below. The latch device 14 comprises a U-shaped bracket 20 having laterally spaced walls 22 and 24 interconnected

2

by a transverse wall 26, said wall 24 defining a face plate which is flush with the surface of the outer side 28 of the stile. The walls 22 and 24 have aligned apertures 30 and 32, respectively, extending therethrough, the latter aperture being elongated in a substantially horizontal plane. The latching member 34 is mounted to the bracket 20 for pivotal bodily movement and for axial reciprocation, said latching member having a central part 36 of quadrilateral cross section and end parts 38 and 40 of circular cross section. The end part 38 extends loosely through the aperture 30 and is adapted to project into the closed bottom aperture 42 of the stile. The end part 40 extends through the elongated aperture 32 and normally projects beyond the surface of the side 28 of the stile.

Secured to the wall 26 of the bracket 20 by a rivet 44 is a leaf spring 46 which biases the latching member 34 in a horizontal plane, said spring having an arcuate end portion 48 which interengages in the V-groove 50 in the normal projected position of said latching member as shown in Fig. 1. The latching member is axially retractible for sash removal from the window frame and is axially projectible to a sash locked position as shown in Fig. 2 in which the spring end portion 48 is partially disengaged from its companion groove. The jamb 52, companion to the latch device 14, corresponds in all respects to the jamb 300 of my above referred to copending application and is routed to define the longitudinal groove 54, the latter having a sash track member 56 suitably secured therein. The track member 56 has a series of vertically spaced shoulder portions 58 adapted for releasable interengagement with end part 40 for releasably positively latching its companion sash at corresponding levels. Sound absorbing pads 60 are suitably secured adjacent to the shoulder portions 58 for deadening the sound of the latching member engaging said shoulder portions. The track members are provided with end portion locking recesses with registering recess portions being provided in the jamb for the reception of a companion latching member 34 for locking the sashes in a closed or slightly opened position as described in detail in my copending application.

In order to lock the sash 12 in a sash locked position, in which end part 40 is disposed in a track member locking recess and registered jamb recess portion as shown in Fig. 2, and in a burglarproof manner, the finger piece 62, which is normally utilized for manipulating the latching member, is threadedly disengaged from the part 36 and a lock screw 64 is substituted therefor. The lock screw 64 is threaded through the tapped aperture 66 and extends through a registering aperture 68 in the spring 46 into abutting relation with the wall 26 of the bracket. The edge 70 of the spring 46, which defines the aperture 68, forms a lock screw stop which prevents the axial retraction of the latching member and vertical sash movement. As shown in Fig. 2, the latching member is preferably disposed at an angle to the face of the sash stile and the wall 26 of the bracket so that the lock screw will wedge against said wall if axial retraction of the latching member is attempted. The lock screw, in its locking position, abuts the wall 26 and prevents the pivotal bodily movement of the latching member and sash release.

Pursuant to the present invention, the front exposed surface 72 of the part 36 of the latching member is knurled or serrated with a multiplicity of uniformly spaced projecting portions 74, the latter being of any suitable design or configuration such as conical configuration with a pointed apex as shown in the illustrated embodiment of Figs. 1-4. The lock screw head 76 is slotted as indicated at 78 and is disposed in flush relation with the surface 72 of the latching member in the locking position of the lock screw. The head 76 corresponds to

the projecting portions 74 and is of conical configuration with a pointed apex so as to render lock screw removal burglarproof from a position without frontal visual access thereto. Thus in the locked condition of the lock screw accurate registration of a screwdriver with slot 78 is required to remove the lock screw and this may be easily effected by one from an inside position or from inside the building structure but becomes a difficult or near impossible task for a burglar who must gain access to the lock screw from an outside position, as by breaking a window pane. Even if the burglar is sufficiently accomplished to know that lock screw removal is required for unlocking a sash, he will be frustrated in his attempt to remove the lock screw without frontal visual access thereto, and thus the latching device provides a burglarproof sash lock. With the lock screw in the locked condition, the front surface 72 presents a uniform feel to the touch or to a screwdriver throughout the area thereof to therefore render the locating of the lock screw head near impossible without frontal visual access. The lock screw may be disposed at any position relative to the part 36 of the latching member.

Secured in the elongated opening 80 of the sash stile is a trim plate 82 which comprises an outer plate 84 and a recessed part 86, the latter interfitting in said opening. The outer plate 84 is secured to the sash stile in flush relation therewith and the rear wall 88 of the recessed part is provided with an elongated opening 90 for the extension therethrough of the finger piece 62 and the lock screw replacement therefor, said rear wall having a peripheral gasket 92 secured thereto and in adjacent relation with the latching member for deadening the sound between said rear wall and the latching member. The part 36 of the latching member is accessible through the trim plate and the finger piece 62 is normally secured to said part for actuating the latter, said finger piece being removed and a lock screw substituted by the householder when it is desired to lock the sashes in a burglarproof manner.

The latching member is preferably disposed at an angle to the face of the sash stile and the plate 84 to render it more difficult to engage the lock screw head with a screwdriver from a blind position and thus to further frustrate a would-be burglar.

With reference to Figs. 5 and 6, there is shown a slightly modified form of latching member 34' which differs from the latching member 34 in the provision of a lock screw 64' having a flat type head 76' which is knurled or serrated corresponding to the knurling or serrations of the front surface 72'. Thus the lock screw head 76' and the front surface 72' are knurled in a corresponding manner to render lock screw removal burglarproof from a blind position.

With reference to Fig. 7, there is shown another modified form of latching member 34" which differs from the latching members previously described in the respects now to be described. The lock screw has a conventional flat head 76" which is slotted as indicated at 78" and said head is in flush relation with the planar surface 72" in the locking position of the lock screw. The surface 72" is provided with a series of randomly arranged dummy slots 79 which dimensionally correspond to the slot 78" of the lock screw head and it will be appreciated that the would-be burglar is faced with a near impossible task to locate slot 78" from a blind position. It will be understood that any standard lock screw head, such as an Allen head, may be utilized pursuant to the present invention in which case the dummy screw heads randomly arranged along the surface 72" will correspond to the lock screw head to render the locating of the lock screw head with a companion tool most difficult, if not impossible, from a blind position.

A latch device, incorporating an anti-burglary feature of the character described above, may be used with any

of the known types of removable sash windows having laterally movable runners and if desired, such latch device may even be used with non-removable sash windows. With reference to Fig. 8, there is shown a modified form 5 of latch device 14' which differs from latch device 14 in the respects now to be described. Latch device 14' comprises a U-shaped bracket 20' having aligned circular apertures 30' and 32' which mount the latching member 34"" for axial movement. The latching member 10 34"" has a central part 36"" which corresponds to the part 36 previously described and incorporates a similar anti-burglary feature utilizing a similar lock screw 64. The stop member 94 for the lock screw is suitably secured to the bracket 20' and is constituted by an angle 15 part which prevents the axial retraction of the latching member. The latching member includes end parts 38"" and 40"" of circular cross section, said part 38"" being surrounded by a coiled compression spring 96 which extends between the wall 22"" and the peripheral shoulder 20 98 of the part 36", said spring being effective to bias the latching member to the right viewing Fig. 8 and in a latching direction. The jamb 100 is provided with a series of vertically spaced apertures 102 defined by the 25 sound absorbent sleeves 104, said apertures being adapted for the reception of the part 40"" for releasably latching the sash at selected levels. In order to lock the sash in a sash locked position and in a burglarproof manner, the part 40"" is engaged in an aperture 102 at a level in which the sash is closed or near closed and the lock screw 64 is substituted for the normally used finger piece 30 in the aforescribed manner. The apertures 102 may be disposed in a jamb or fixed or movable runner and the latching member may be provided with any of the 35 types of anti-burglary constructions described above. It will be understood that with the lock screw removed, the sash may be vertically adjusted by manipulating the latching member in the direction of the arrow against the action of the spring 96 to disengage the part 40"" from an associated aperture 102. As in the case of the latch 40 device 14, a trim plate 82"" is secured to the sash stile to expose the part 36"" of the latching member in the manner described above in detail.

If desired, the latch device 14 may have a suitable 45 part or device, such as a plastic block, secured to the inside surface of the wall 26 in alignment with the lock screw 64 so as to insure the tightness of the lock screw when the head thereof is in flush relation with the surface 72 of the latching member. Such plastic block may be apertured for the reception of the end of the lock screw 64, the latter forming its own threads in the block and being received tightly therein for the aforesaid purpose.

While there is shown and described herein certain specific structure embodying the invention it will be manifest to those skilled in the art that various modifications and rearrangements of the parts may be made without departing from the spirit and scope of the underlying inventive concept and that the same is not limited to the particular form herein shown and described except insofar as indicated by the scope of the appended claims.

Having thus described my invention what I claim as new and desire to secure by Letters Patent is:

1. A latching device, comprising a bracket mounting a latching member for axial movement between first and second positions, and means for locking said latching member in one of said positions thereof comprising abutment means disposed in fixed relation with said bracket and a lock screw carried by said latching member disposed for engagement with said abutment means in the locking position thereof, said lock screw having a slotted head which is disposed in substantially flush relation with adjacent surface portions of said latching member in the locking position of said lock screw, said latching member surface portions having surface interruptions corresponding to said lock screw head in the region of the

latter whereby to render lock screw removal burglarproof from a position without frontal visual access thereto.

2. A latching device, comprising a bracket mounting a latching member for axial movement between first and second positions, and means for locking said latching member in one of said positions thereof comprising abutment means carried by said bracket and a lock screw carried by said latching member disposed for engagement with said abutment means in the locking position thereof, said lock screw having a slotted head which is disposed in substantially flush relation with adjacent surface portions of said latching member in the locking position of said lock screw, said latching member surface portions being serrated corresponding to said lock screw head in the region of the latter whereby to render lock screw removal burglarproof from a position without frontal visual access thereto.

3. A latching device, comprising a bracket mounting a latching member for axial movement between first and second positions, and means for locking said latching member in one of said positions thereof comprising abutment means disposed in fixed relation with said bracket and a lock screw carried by said latching member disposed for engagement with said abutment means in the locking position thereof, said lock screw having a slotted head which is disposed in substantially flush relation with adjacent surface portions of said latching member in the locking position of said lock screw, said latching member surface portions being serrated with a multiplicity of spaced projecting portions, and said lock screw head having a terminal end part corresponding to said projecting portions whereby to render lock screw removal burglarproof from a position without frontal visual access thereto.

4. A latching device, comprising a bracket mounting a latching member for axial movement between first and second positions, and means for locking said latching member in one of said positions thereof comprising abutment means carried by said bracket and a lock screw carried by said latching member disposed for engagement with said abutment means in the locking position thereof, said lock screw having a slotted head which is disposed in substantially flush relation with adjacent surface portions of said latching member in the locking position of said lock screw, said latching member surface portions being serrated with a multiplicity of spaced projecting portions, and said lock screw head having a terminal end part corresponding to said projecting portions whereby to render lock screw removal burglarproof from a position without frontal visual access thereto, said end part and projecting portions being of generally conical configuration with a substantially pointed apex.

5. A latching device, comprising a bracket mounting a latching member for axial movement between first and second positions, and means for locking said latching member in one of said positions thereof comprising abutment means carried by said bracket and a lock screw carried by said latching member disposed for engagement with said abutment means in the locking position thereof, said lock screw having a slotted head which is disposed in substantially flush relation with adjacent surface portions of said latching member in the locking position of said lock screw, said latching member surface portions and said lock screw head being serrated with a multiplicity of spaced projecting portions whereby to render lock screw removal burglarproof from a position without frontal visual access thereto.

6. A latching device, comprising a bracket mounting a latching member for axial movement between first and second positions, and means for locking said latching member in one of said positions thereof comprising abutment means carried by said bracket and a lock screw carried by said latching member disposed for engagement with said abutment means in the locking position thereof,

said lock screw having a slotted head which is disposed in substantially flush relation with adjacent surface portions of said latching member in the locking position of said lock screw, said latching member surface portions having a plurality of randomly arranged slots corresponding to said lock screw head slot whereby to render lock screw removal burglarproof from a position without frontal visual access thereto.

7. A latching device, comprising a bracket mounting a latching member for axial movement between first and second positions, and means for locking said latching member in one of said positions thereof comprising abutment means disposed in fixed relation with said bracket and a lock screw carried by said latching member disposed for engagement with said abutment means in the locking position thereof, said lock screw having a head of predetermined configuration which is disposed in substantially flush relation with adjacent surface portions of said latching member in the locking position of said lock screw, said latching member surface portions having surface interruptions corresponding to said lock screw head head in the region of the latter whereby to render lock screw removal burglarproof from a position without frontal visual access thereto.

8. A latching device for a window construction of the character described, comprising a bracket having aligned apertures, a latching member mounted for axial movement in said aligned apertures, said latching member having an end portion thereof extending through one of said apertures and laterally beyond the surface of a companion wall of said bracket in a projected position, said latching member being axially movable from said projected position to a retracted position in which said projecting portion is retracted inwardly of said bracket, and means for locking said latching member in said projected position comprising abutment means carried by said bracket and a lock screw carried by said latching member disposed for engagement with said abutment means in the locking position thereof, said lock screw having a slotted head which is disposed in substantially flush relation with adjacent surface portions of said latching member in the locking position of said lock screw, said latching member surface portions having surface interruptions corresponding to said lock screw head whereby to render lock screw removal burglarproof from a position without frontal visual access thereto.

9. A latching device for a window construction of the character described, comprising a bracket having aligned apertures, a latching member mounted for axial movement in said aligned apertures, said latching member having an end portion thereof extending through one of said apertures and laterally beyond the surface of a companion wall of said bracket in a projected position, said latching member being axially movable from said projected position to a retracted position in which said projecting portion is retracted inwardly of said bracket, and means for locking said latching member in said projected position comprising abutment means carried by said bracket and a lock screw carried by said latching member disposed for engagement with said abutment means in the locking position thereof, said lock screw having a slotted head which is disposed in substantially flush relation with adjacent surface portions of said latching member in the locking position of said lock screw, said latching member surface portions having surface interruptions corresponding to said lock screw head whereby to render lock screw removal burglarproof from a position without frontal visual access thereto, said latching member surface portions being serrated with a multiplicity of spaced projecting portions, and said lock screw head having a terminal end part corresponding to said projecting portions.

10. A latching device for a window construction of the character described, comprising a bracket having aligned apertures one of which is elongated in one plane,

a latching member mounted for pivotal bodily movement in said plane in said aligned apertures, said latching member having an end portion thereof extending through said elongated aperture and extending laterally beyond the surface of a companion wall of said bracket, means carried by said bracket for resiliently biasing said latching member in said plane towards one end of said elongated aperture, said latching member being axially movable from said position in which said projecting portion extends laterally beyond said wall surface to a retracted position in which said projecting portion is retracted inwardly of said bracket from said first mentioned position, and means for locking said latching member in said first mentioned axial position and disposed at said one end of said elongated aperture, said means comprising abutment means carried by said bracket and a lock screw carried by said latching member disposed for engagement with said abutment means in the locking position thereof, said lock screw having a slotted head which is disposed in flush relation with adjacent surface portions of said latching member in the locking position of said lock screw, said latching member surface portions having surface interruptions corresponding to said lock screw head whereby to render lock screw removal burglarproof from a position without frontal visual access thereto.

11. A latching device for a window construction of the character described, comprising a U-shaped bracket having laterally spaced walls and a connecting transverse wall, said laterally spaced walls having aligned apertures one of which is elongated in a direction towards said transverse wall, a latching member mounted for pivotal bodily movement in said direction in said aligned apertures, said latching member having an end portion thereof extending through said elongated aperture and extending

10

15

20
